UNITED STATES PATENT OFFICE.

JOHN H. HENDRICK, OF DENVER, COLORADO.

ADJUSTABLE BED.

1,156,359.

Specification of Letters Patent.

Patented Oct. 12, 1915.

Application filed October 10, 1914. Serial No. 866,053.

To all whom it may concern:

Be it known that I, JOHN H. HENDRICK, a citizen of the United States, residing at Denver, in the county of Denver and State of Colorado, have invented certain new and useful Improvements in Adjustable Beds, of which the following is a specification.

My invention relates to a new and useful adjustable bed, and its object is to mount a bed in such a relation to the window of a sleeping chamber, that it may be used either within the chamber or just outside the window, the occupant of the bed deriving in the latter case the sanitary effects of out-door sleeping.

Another object is to so arrange my novel bed that it may when not in use, be disposed in an upright position adjacent to the window within the sleeping chamber.

A further object is to correlate with the bed a mechanism that will minimize the amount of exertion necessary to shift the bed from one of its several positions to another.

A still further object of the invention is to provide a device of the character described, that will be strong, durable, efficient and simple and comparatively inexpensive to produce, also one in which the several parts will not be likely to get out of working order.

With the above and other objects in view, the invention has relation to certain novel features of construction and operation, an example of which is described in the following specification and illustrated in the accompanying drawings, wherein:

Figure 1 is a view showing the bed in the upright position which it occupies when not in use. Fig. 2 is an exterior view of the window with which my novel bed is correlated, showing the screened sleeping compartment provided just outside of the window. Fig. 3 is a view showing in side elevation the bed adjusted for use within the sleeping chamber, the window being shown in section. Fig. 4 shows in side elevation the bed shifted into the exterior sleeping compartment, the window being again shown in section. Fig. 5 is a fragmentary view showing in side elevation the position occupied by the bed when shifted midway between its interior and exterior positions of use. Fig. 6 is a vertical sectional view taken upon the line $a-a$ of Fig. 4, the pivotal connections between the bed and its swinging supports being shown.

Fig. 7 is a fragmentary sectional view taken on $b-b$ of Fig. 3. Fig. 8 is a section on $c-c$ of Fig. 1, showing one end of the bed. Fig. 9 is a detail section on $d-d$ of Fig. 8, primarily showing the fastening device employed to maintain the bed upright. Fig. 10 is a detail vertical section on $e-e$ of Fig. 7 showing a certain push button mechanism used in conjunction with my bed. Fig. 11 is a detail vertical section on $f-f$ of Fig. 7 showing another push button mechanism.

Referring now more particularly to the drawings, wherein like reference characters designate similar parts in all the figures, the numeral 1 denotes the frame of a sleeping chamber window, and the sliding sashes of said windows are indicated at 2.

Within the sleeping chamber, vertically elongated casings 3 are provided at each side of the window being extended to the upper portion thereof from the floor. One wall of each of said casings is mirrored and is hinged as shown at 4, forming a door giving access to the casing interior. At a level slightly above the sill of said window, a bench 5 is permanently mounted between the casing 3, to support either an extremity of a bed 6 or the entire bed, depending upon the adjustment of the latter. The bed 6 is adapted to occupy either of three positions, which are respectively illustrated in Figs. 1, 3 and 4. In Fig. 1 the bed is shown standing on end upon the bench 5, fitting between the casings 1. When the bed is not in use it will preferably be adjusted to this position, in which it is out of the way and permits the sleeping chamber to be used as a sitting room. A large mirror 7 mounted in the bottom face of the bed will be found useful when the bed occupies the position illustrated in Fig. 1.

When the bed is horizontally disposed within the sleeping chamber, as shown in Fig. 3, it rests at one extremity upon the bench 5, while its other end is supported by a pair of legs 8. When these legs are not in use they are adjusted as shown in Fig. 8, extending toward each other contiguous with the correlated end face of the bed, the adjacent ends of the legs being engaged with each other by a hook and eye fastening 9. In order that the legs may be shifted from their position of use to the position shown in Fig. 8, pivot pins 10 are employed to mount the legs upon the bed. As shown in Fig. 3 the bed is adjusted for use within the sleep-

ing chamber. In the third position, illustrated in Fig. 4, the greater portion of the bed is exterior to the sleeping chamber, supported in a manner hereinafter described. 5 In this position, one end of the bed projects through the window into the sleeping chamber where it rests upon the bench 5. A person using the bed in this adjustment derives the sanitary benefits of out-door sleeping 10 and avoids the close or heated atmosphere of the sleeping chamber.

The means provided to facilitate shifting the bed between its various positions of adjustment will now be described. Adjacent to each side of the bed there is provided an arm 11, one end of which has pivotal connection with the correlated side of the bed at the center thereof. The other ends of the arms 11 are respectively hung 20 on tubular pivot members 12, mounted in the opposing walls of the casing 3, just above the bench 5. The arms 11 swingingly support the bed while the same is being manually shifted from its interior to its 25 exterior position of use or vice versa. While the bed is being so shifted, it is manually maintained substantially horizontal, its motion being gradually upward to the intermediate position shown in Fig. 5 and then gradually downward to either limiting positions. The arms 11 are so proportioned that sufficient space for the passage of the bed through the window is obtained by 30 adjusting the lower sash 2 in the raised position which it is shown to occupy in the drawings.

In order to decrease the amount of manual exertion required to move the bed from one of its positions to another, counter-balancing weights 13 are employed, these weights being respectively suspended within the casing 3, within which they may work up and down. The weight cords 14 are carried over pulleys 15 as they pass 45 through suitable orifices in the opposing walls of the casings 3, and are then respectively extended to the pivot screws 16 by which the arms 11 are connected to the bed. While the bed is being upwardly displaced 50 in adjustment between any of its three positions, the pull of the weights 13 will so supplement the manually exerted force that the latter need be only slight. Similarly said weights will pull back upon the bed 55 when it is undergoing downward displacement, during adjustment, so that a slight physical effort will be sufficient to control its motion.

In shifting the bed from its position for 60 interior use (see Fig. 3) to its position of non-use (see Fig. 1) or vice versa, it is desired to swing the bed about an axis passing through the extremity resting upon the bench 5. This axis is established in coincidence with the axis of the pivot members 65

12, by slightly shifting rods 17 extending within said members 12, so that the ends of said rods 17 enter suitable sockets 18 formed in the correlated extremity of the bed at each side thereof. Each rod 17 70 passes through the correlated casing 3 and carries a push button 19 exterior to said casing which when pressed actuates the rod into the correlated socket 18. To disengage said rods from the sockets 18, they are respectively correlated within the casing 3 75 with intermediately pivoted levers 20, each having one end pivotally engaging the correlated rod 17, while its other end pivotally engages a short rod 21, extending exterior 80 to the casing and carrying a button 22. A slight pressure exerted upon either button 22 suffices to disengage the correlated rod 17 from its socket 18 (see Fig. 10). That extremity of the bed in which the sockets 85 18 are formed has its lower edge rounded as indicated at 23, so that contact of said edge with the bench 5 will not prevent the bed from being swung about an axis established by the rods 17.

In order to securely hold the bed adjusted in any of its three positions, there are employed locking mechanisms, which will now be described. Closely adjacent to each rod 17, a parallel rod 24, passes through each 90 casing 3, and in one limiting position of sliding displacement is adapted to enter one of two sockets 25 formed in the adjacent arm 11, as is seen in Fig. 11. Each rod 24 carries a button 26 exterior to the correlated 95 casing and is associated with a centrally pivoted lever 27 and auxiliary push rod 28 100 similar to the members 20 and 21 already described. Pressure upon the buttons 26 serves to engage the rods 24 each in one of 105 the sockets 25, provided the bed is adjusted in one of its two positions of use. When the arms 11 are thus engaged with the casing 3 at points other than those establishing pivotal connection between the arms 110 and casings, obviously the arms are locked in a rigid relation with the casing, so that the bed may not be shifted. To lock the bed in its upright position, a rock-shaft 29 is mounted upon that end of the bed which is 115 uppermost when the bed is upright and hooks 30 formed upon the ends of said rock-shaft are adjusted to engage eye-bolts 31 120 mounted in the top member of the window frame. A leaf spring 32 mounted upon the bed adjacent to the rock-shaft 29 and midway between the ends thereof, subjects the rock-shaft to a rotative impulse such as will maintain the hooks 30 engaged with the eye-bolts 31 when the bed is upright.

The exterior sleeping compartment which receives the bed when adjusted as shown in Fig. 4 will now be described. The framework of this compartment comprises two similar upper and lower U-shaped members 125 130

33, the corners of which are rigidly connected by vertical members 34. The free ends of the members 33 respectively carry hooks 35, which engage brackets 36 secured 5 to the window casing. Walls are formed on three sides of the compartment by foraminous fabrics 37, preferably of screen wire which extends between the two members 33. A pair of cross bars 38 extending 10 rigidly between the parallel portions of the lower member 33 support the outer portion of the bed when the same is extended into the sleeping compartment. From the outer end of the upper member 33, a pair of 15 chains 39 extend at an inclination to the upper portion of the window casing, being secured to each side thereof. The compartment is completed by an ordinary awning 40 having the usual side curtains 41.

20 All the advantages of a screened sleeping porch are afforded by the above-described invention at an expense much less than is ordinarily involved in building such a porch.

25 The invention is presented as including all such modifications and changes as properly come within the scope of the following claims.

What I claim is:

30 1. In a device of the character described, the combination with a bed adjustable through a window between two positions of use respectively interior and exterior to a sleeping chamber, of a pair of vertically 35 elongated casings disposed respectively at each side of the window within the sleeping chamber, a bench extending between said casings substantially at the level of the window sill, said bench supporting one end of 40 the bed in either specified position and also in a third upright position, and weights arranged within the two casings to counter-balance the bed when the same is being elevated or lowered.

45 2. In a device of the character described, the combination with a bed adjustable through a window between two positions of use respectively interior and exterior to a sleeping chamber, of a bench mounted adjacent to the sill of said window and substantially on a level with said sill, said bench supporting one extremity of the bed in either of its specified positions and supporting the entire bed in a third upright position, and means engaging the bed to maintain it in its upright position.

50 3. In a device of the character described,

the combination with a bed, adjustable through a window between two positions of use respectively interior and exterior to 60 a sleeping chamber, of a pair of swinging arms correlated with the bed at each side of the same, each having one of its extremities pivotally engaging one side of the bed and having its other end pivotally mounted 65 adjacent to the lower portion of the window frame, and casings arranged adjacent to the window frame and pivotally supporting said arms.

4. In a device of the character described, 70 the combination with a bed adjustable through a window between two positions of use respectively interior and exterior of a sleeping chamber, of a pair of arms disposed at each side of the bed, supporting the 75 same while being adjusted, and a sleeping compartment outside of the window inclosing the bed in its exterior position, said arms and bed arranged to swing through the window frame and sleeping compartment in 80 varying the positions of use of said bed.

5. In a device of the character described, the combination with a bed, adjustable through a window between two positions of use, respectively interior and exterior to 85 a sleeping chamber, of a pair of vertically elongated casings, disposed at each side of the window within the sleeping chamber, a bench mounted between said casings substantially level with the window sill, sup- 90 porting one extremity of the bed in either of its specified positions, the bed being also adaptable to a position upright upon said bench, a pair of arms correlated with the bed at each side of the same, each having 95 one of its extremities pivotally engaging one of said casings just above said bench, and having its other end pivotally engaging the adjacent side of the bed midway between the ends of the same, weights ar- 100 ranged within said casings to counter-balance the bed, means for locking said arms in either of their two horizontal positions, and means for engaging the extremities of 105 said arms which are pivotally mounted on the casing, with the adjacent extremity of the bed.

In testimony whereof I have signed my name to this specification in the presence of two subscribing witnesses.

JOHN H. HENDRICK.
